UNITED STATES PATENT OFFICE.

JULIUS HORTVET, OF MINNEAPOLIS, MINNESOTA.

SUBLIMATOR.

Application filed February 10, 1923. Serial No. 619,952.

To all whom it may concern:

Be it known that I, JULIUS HORTVET, a citizen of the United States, residing in Minneapolis, in the county of Hennepin and State of Minnesota, have invented a new and useful Sublimator, of which the following is a specification.

The increased utility of the process of sublimation in laboratories coupled with the commercial possibilities thereof has been attended with the need of practical apparatus for separating and purifying substances in large as well as in small quantities and for general quantitative and microscopic analysis.

My invention relates to improvements in sublimators, its object being to provide a simple and durable apparatus of this kind which is convenient and efficient in operation and readily adaptable to the various conditions met in the different uses to which it may be put.

With the foregoing and other objects in view, which will appear in the following description, the invention resides in the novel combination and arrangement of parts and in the details of construction hereinafter described and claimed.

In the drawings, Fig. 1 is a plan view of a laboratory device embodying my invention; Fig. 2 is a sectional view illustrating the heater, the same being taken as on the line 2—2 of Fig. 1; Fig. 3 is a sectional view taken on the line 3—3 of Fig. 1, the lower portion of the heater being broken away; Fig. 4 is a detail sectional view taken on the line 4—4 of Fig. 3; Fig. 5 is a vertical sectional view in detail illustrating a portion of the body section and the base section of the sublimation vessel, also a capsule, stand therefor and microscopic slide employed for microsublimations and Fig. 6 is a plan view in detail of the stand or block to support vessels for substances in the base section of the sublimation vessel.

Referring to the drawings, it will be observed that my improvement includes a heater A and a sublimation vessel B, which is removably supported by the heater. The heater A includes a base 10 and a cylindri-

cal jacket 11 rising therefrom. Within the upper end of the jacket 11 is a heating drum a, the side wall thereof comprising a sleeve 12, which is smaller in diameter than the jacket 11 and arranged in axial alignment with respect thereto. This sleeve 12 has an outwardly extending annular shoulder 13 resting upon the upper edge of the jacket and supporting said sleeve therein. An annular cover-plate 14 having a central vessel 60 receiving opening 15 therein forms the top of the drum. This cover-plate caps the sleeve 12, its margin being turned downward over a depending annular flange 16 on the shoulder 13, thence turned upward within 65 said flange to join the cover-plate with the sleeve structure and to form a rib for the reception of set screws 17, the inner ends of which engage beneath a bead 18 at the upper edge of the jacket 11. The bottom of 70 the drum consists of a cup-like tray 19 fitting closely within the sleeve 12 and slidable vertically therein. This tray 19 is supported at various elevations within the sleeve 12 by means of hanger rods 20. These rods, secured at the lower ends to the sides of the tray 19, slide up and down within hollow posts 21 rising from the cover plate 14, said posts being equipped with binding screws 22 to grip said rods 20 and the rods being 75 equipped with handles 23 for manipulating the same in raising and lowering the tray 19. Rising from the cover-plate 14 is a standard 24 having a vertically adjustable clip 25 thereon. This clip slidably grips a 80 thermometer 26 reaching downward through a notch 27 in the cover-plate 14 and into a sand bath 28 in the tray 19. The jacket 11 has an opening 29 in the side thereof to receive a burner 30, which is removably seated 85 on the base 10 in position beneath the bottom of the drum a.

The sublimation vessel B is removably seated in the drum a as shown in Fig. 3, more or less of the lower portion of said vessel being encased within said drum, as desired, upon appropriate manipulation of the hanger rods 20. Said vessel includes a cylindrical body section b and a base section c. The body section has a dome-like top ter- 100

minating in an axial nipple 31, the lower end of said section being open and the side wall contracted slightly at its extremity to form a beveled annular shoulder 32. The 5 base section *c* is a cup-like structure having an annular lip 33 to fit snugly over the shoulder 32 of the body section *b* and seal the open end thereof. Said section *c* comprises a removable subliming cup for the 10 reception of substances to be treated. Such substances are preferably placed in a dish, as at 34, Fig. 3, a stand 35 being supplied to elevate the same, if necessary.

For purposes hereinafter explained, a diaphragm 36 of platinum gauze or other suitable material is removably placed upon supporting lugs 37 projecting inwardly from the margin of the shoulder 32. In some operations the diaphragm is omitted and a 20 relatively tall capsule, as at 38, Fig. 5, is seated in a central bore 39 in the stand 35. Within the upper end of the body section *b* is an accumulator consisting of an axially arranged bulb *d*. Inlet and outlet conduits 25 40 and 41 communicating with said bulb at its upper end reach upward through the top of the body section *b* then turn outward in opposite directions. Said conduits form hangers for the bulb *d*, the inlet conduit 40 30 being extended downward axially of the bulb and terminating at a point near the bottom thereof (Fig. 3). The inlet conduit 40 is designed to be detachably connected with a supply pipe or hose (not shown) for a 35 cooling fluid, while the outlet conduit 41 is designed to be detachably connected with a suitable drain pipe or hose (not shown).

In use, a substance to be treated for the purpose of separating a purified material 40 therefrom or for the purpose of quantitative analysis, is placed in a dish 34 in the subliming cup *c*. The diaphragm 36 is applied to the body section *b*, as shown in Fig. 3, and the dish elevated, if desired, by 45 the use of the stand 35 to bring the rim of the dish into close proximity to the diaphragm. The sublimation vessel *B* is seated in the drum *a* (Fig. 3), the subliming cup *c* being nested in the sand bath 28. The tray 50 19 is lowered from elevated receiving position to encase the desired portion of the vessel *B* in the drum *a*, the thermometer 26 being correspondingly adjusted. The inlet and outlet conduits 40 and 41 are connected 55 with inlet and drain pipes, respectively, and the nipple 31 is connected with a tube leading to a vacuum pump or other suitable pressure reduction device, said tube, if desired, being threaded through the eye 42 in 60 the support 24. After lighting the burner 30 and guided by readings of the thermometer 26, the user accurately adjusts said burner to accord with the work or experiment conducted. The sublimed material accum-

ulates on the lower portion of the bulb *d*, 65 any part of such material dislodged therefrom being caught upon the diaphragm 36. Upon completion of the sublimating process, the pipes to the conduits 40 and 41 are disconnected and said conduits suitably 70 plugged. The nipple 31 is also disconnected from the vacuum tube. The sublimation vessel *B* is then lifted from the heater and after cooling the cup *c* is detached from the body section *b*. Said section is then inverted 75 without the removal of the diaphragm, which falls loosely into the space between the bulb *d* and shell of the body portion *b*. By means of a suitable solvent, the deposit on the bulb is washed through the nipple 31 80 into a crystallizing receptacle, the dissolved sublimate being thereafter suitably treated to attain the desired ends. In this connection attention is invited to the fact that the nipple 31 serves not only as a conduit for 85 the exhaustion of air from the sublimating vessel *B*, but also as a drain for sublimate washed from the sublimation chamber within the body section *b*.

For microsublimation, when only a very 90 small quantity of sublimable material is probably present, the substance is placed in the narrow base portion of the subliming capsule 38 (Fig. 5), said capsule being seated in the bore 39 in the stand 35 within the 95 cup *c*. A glass slide 43 initially placed so as to rest on lugs 37 in the body section *b* is lifted by and covers the capsule 38 when the cup *c* is applied to said body section. Said slide, being in proximity to the cooling bulb 100 *d*, serves as an accumulator for material sublimed from the substance in said capsule. For such microsublimation, the tray 19 is 105 adjusted to an elevation encasing the cup *c* and only a small portion of the body section *b* of the vessel *B*. The cooling fluid pipes are connected to the conduits 40 and 41 and the vacuum tube is connected with the nipple 31 as above explained. Sublimation being completed, the vessel *B* is removed from 110 the heater *A* and, after cooling, the cup *c* is detached from the body portion *b*. The slide 43 then being accessible, may be removed and the sublimate thereon examined under a microscope without the use of a cover-glass. 115

Changes in the specific form of my invention, as herein disclosed, may be made within the scope of what is claimed without departing from the spirit of my invention. 120

Having described my invention, what I claim as new and desire to protect by Letters Patent is:

1. In a device of the class described, a vessel adapted to contain a substance in the bottom thereof to be treated, means for heating the lower portion of the vessel, said vessel having an elevated opening therein for the 125

exhaustion of air therefrom and an accumulator within said vessel presenting a surface for the deposition of material sublimed from said substance under heat, within the vacuous interior of the vessel.

2. In a device of the class described, a vessel adapted to contain a substance in the bottom thereof to be treated, means for heating the lower portion of the vessel, said vessel having an opening at the top thereof for the exhaustion of air therefrom, an accumulator bulb spaced centrally within the upper portion of said vessel, said bulb supplying a surface for the deposition of material sublimed from said substance under heat, within the vacuous interior of the vessel, an inlet duct for a cooling fluid leading into said bulb and an outlet duct for said fluid leading from said bulb.

20 3. In a device of the class described, a vessel adapted to contain a substance to be treated in the bottom thereof and formed with an elevated opening serving, in the normal position of the vessel, as an outlet for the exhaustion of air therefrom and, in the inverted position of said vessel, as a drain, means for applying heat to the vessel and a cooled surface within the vessel for the deposition of material sublimed from said substance.

25 4. In a device of the class described, a vessel comprising an elongated body section and a cup-like base section removable therefrom, said base section being adapted to contain a substance to be treated, said body section having an opening in the top thereof serving, in the normal position of the vessel, as an outlet for the exhaustion of air therefrom and, in the inverted position 30 of said body section, as a drain, a bulb spaced centrally in the body section near the top thereof, inlet and outlet conduits communicating with said bulb through the walls of the body section and supporting the bulb 35 within said section, the inlet conduit being extended centrally downward in the bulb to discharge against the bottom thereof, the lower portion of the bulb supplying a surface for the deposition of material sublimed 40 from said substance, and a drum for encasing the lower part of the vessel, said drum having a bottom supplying a rest for the vessel, said bottom being adjustable vertically to vary the area of the vessel 45 encased in said drum and a burner beneath the drum for heating the same.

5. A vessel comprising a body section and a closely fitting cup-like base section, the latter being removable from the former to be charged with substances and emptied of the residue thereof after treatment, said body section having an opening therein for the exhaustion of air from said vessel, means for heating the base section of said vessel and

an accumulator within the body section supplying a surface for the deposition of material sublimed from said substance.

6. In a device of the class described, a heating drum, a vessel, said vessel being adapted to be seated in said drum and the lower portion thereof encased thereby, said drum comprising a sleeve-like sidewall, a cover-plate capping the same and formed with an opening freely receiving said vessel, a vertically movable bottom for supporting the vessel and means for lifting and lowering and securing said bottom at various elevations to encase more or less of the vessel within the drum, means for heating the drum, said vessel comprising an elongated shell adapted to contain a substance in the bottom thereof to be treated, said shell having an opening therein for the exhaustion of air therefrom and an accumulator within the shell supplying a surface for the deposition of material sublimed from said substance, under heat, within the vacuous interior of said shell.

7. In a device of the class described, a vessel having an outlet for connection with pressure reduction means, said vessel being adapted to contain a substance in the bottom thereof to be treated, an accumulator elevated within the vessel and presenting a surface for the deposition of material sublimed from said substance, means for cooling the accumulator and a heating drum adapted to encase more or less of the lower portion of said vessel.

8. In a device of the class described, a vessel having an outlet for connection with pressure reduction means, said vessel being adapted to contain a substance in the bottom thereof to be treated, an accumulator elevated within the vessel and presenting a surface for the deposition of material sublimed from said substance, means for cooling the accumulator, a heating drum, said vessel being removably seated in the drum, said drum being adjustable to vary the height at which the vessel is encased thereby.

9. In a device of the class described, a sublimation vessel, a heating drum for the vessel including an upright sleeve, a tray forming the bottom of the drum and supplying a rest for said vessel, said tray being adjustable vertically in said sleeve, a cover-plate capping the sleeve and formed with an opening therein to fit about the sides of the vessel and means for heating the drum.

10. In a device of the class described, an elongated sublimation vessel, a heater including an upright cylindrical jacket having an opening in the side thereof to receive a burner, a heating drum within the jacket and above said burner, said drum comprising an upright sleeve forming the sidewall of the drum, a cup-like tray slidable within

the sleeve, said tray forming a vertically adjustable bottom for the drum and a rest for the vessel, and a cover-plate capping the sleeve and formed with an opening therein to freely receive said vessel.

11. A vessel comprising a body section and a base section removably applicable thereto, the former having an opening at the bottom thereof, said base section comprising a closure for sealing said opening and a recep-

tacle to contain a substance to be treated, means for heating the base section and a jacketed cooling medium within the body section supplying a surface for the deposition of material sublimed from said substance. 15

In testimony whereof, I have signed my name to this specification.

JULIUS HORTVET.
